UNITED STATES PATENT OFFICE.

HARRY BRIDGMAN SMITH, OF BROOKLYN, NEW YORK, ASSIGNOR, BY MESNE ASSIGNMENTS, TO HOAGUE-SPRAGUE CORPORATION, OF LYNN, MASSACHUSETTS, A CORPORATION OF MASSACHUSETTS.

CARD-FEED MECHANISM AND METHOD.

Application filed July 24, 1923. Serial No. 653,505.

My invention relates to mechanism and methods for separating and feeding individual cards or card-board blanks from a stack. While the sheet thickness may vary, 5 the invention is especially adapted for the feeding of sheets or blanks of fibrous material of substantial thickness, such for instance, as cardboard or fibre board blanks suitable for box shells, and is therefore conveniently designated as card feed mechanism.

In various classes of mechanism in the paper working art, cardboard blanks are arranged in stacks and it is necessary to separate and feed individual blanks from the stack. Such feed mechanism may be employed, for example, for feeding blanks to blank cutting or creasing mechanism, gluing mechanism, assembly mechanism in which 15 the cardboard blank is associated with a paper blank to form a composite box blank, or to blank conveying mechanism which carries the blank to box forming mechanism. Difficulty has been experienced in these blank 20 feed mechanisms and especially those which handle cards, that is, blanks having more than ordinary paper thickness, in properly separating the bottom blank from an upright stack and properly advancing it without disturbing the next adjacent blank in the stack. This difficulty is emphasized by the fact that cardboard blanks, when cut from a web which is drawn from a roll, are frequently warped 25 in one direction, they are also frequently cut from superposed sheets so that the edges of the individual blanks are more or less interlocked or "stuck" together in the multiple cutting operation, and especially in the case of blanks which are cornered, or slit to produce flaps or wings, the flaps or wings of adjacent blanks in the stack frequently interlock. In all of these cases the separating and advancing devices heretofore employed 30 frequently fail to separate and advance the end blank at the proper time, or the blank is damaged in the act of separation or advance, or it is only partly advanced and is inaccurately positioned in relation to subsequently-acting devices; and these inaccuracies or failures in the feeding operation 35

subsequently interfere with operations which are subsequently performed, as will be understood by persons skilled in this art, without further explanation.

The general object of this invention is to provide mechanism which will accurately and positively separate and feed individual cards, either flat or warped, of plain rectangular contour, or cornered or slit to provide flaps or wings in one or more edges. In a preferred organization of the machine, advantage is taken of the curvature of warped blanks to separate and feed such blanks with great accuracy and practically no failure; and the feed mechanism may therefore be advantageously employed in a great variety of paper working machines in which the accurate supply of individual blanks at regular intervals without skips or other failures is of great importance in commercial 70 production of box parts or other paper articles.

The organization of the machine is also such that it effectively separates blanks which have their edges more or less interlocked or stuck together, and flapped or winged blanks in which the parts of adjacent blanks are more or less interlocked in the stack.

Another important object of the invention 80 is to produce the stated and other desired results in a bottom feed mechanism, which permits top stack replenishment.

The characteristics and advantages of the invention are further sufficiently explained in connection with the following detail description of the accompanying drawings, which show certain representative embodiments of the invention. After considering these embodiments, persons skilled in the art will understand that many variations may be made within the principles of the invention, and I contemplate the employment of any structures that are properly within the scope of the appended claims.

Figure 1 is a plan view, with some parts in section, of one representative feed mechanism embodying the invention, associated with an automatic box making machine.

Figure 2 is a front elevation of the same.

- 22
- Figure 3 is a vertical longitudinal section. Figure 4 is an enlarged detail in longitudinal section.
- Figure 5 is a perspective view of one typical blank.
- Figure 6 is a section at 6-6 of Figure 5.
- Figure 7 is a section at 7-7 of Figure 5.
- Figure 8 is a perspective positional or explanatory view.
- 10 Figure 9 is a front elevation, with some parts in section, of a modified form of feed mechanism associated in this case with a different representative form of paper-handling or -working machine.
- 15 Figure 10 is a horizontal section of the same at 10-10, Figure 9.
- Figure 11 is a vertical longitudinal section at 11-11, Figure 10.
- The feed mechanism may be designed as 20 a part of any one of a great variety of paper handling or paper working machines, or it may be built up practically as a unit to be incorporated in or applied as an attachment to a particular paper handling or working 25 machine, or may be designed as an attachment suitable for a variety of such machines. As examples of such variations in the general plan or organization of the mechanism, Figures 1 to 8 inclusive, show the feed mechanism in one form as practically incorporated 30 in the front end structure of an automatic box machine of the type disclosed in my Patent No. 1,479,401, January 1, 1924, although the feed mechanism might equally 35 well be designed as a substantially self-contained unit and attached to the front end of such a machine or other paper handling or working machine; and Figures 9, 10 and 11 show the feed mechanism in a modified 40 form associated with the framework and feed rolls of a paper handling machine which is representative of a great variety of mechanism in this art. In the latter case the feed mechanism, while not actually a 45 self-contained unit, since it comprises base or frame members which are connected to the framework of the paper working machine to which it is attached, may obviously 50 be arranged as a self-contained unit by providing a suitable base for the feed mechanism proper.
- In the first representative form of the invention, Figures 1 to 8 inclusive show the front ends 1 of side frame members of an 55 automatic box part assembling and forming machine of the type above referred to. These frame members support vertically movable tracks 2 on which a blank transfer carriage 3 is arranged to reciprocate.
- 60 A box-shell or body-blank gripping head 4 is connected to the carriage, this head being provided on its lower face with stencil members 5 contoured in accordance with the outline of the blank. Means are also provided, sufficiently represented by the air 65 tube 6, for exhausting air from the interior space of head 4, which may be descriptively identified as a suction head, to assist in securing the blank to the lower head surface during blank transfer. The framework also 70 supports a vertically immovable rack bar 7 which reciprocates in guides 8. A vertical, slotted bracket 9 is carried by the rack bar, carriage 3 being provided with a roller 10 engaging in the bracket slot so that the 75 carriage is reciprocated by the movements of the rack bar and may also rise and fall as rails 2 are raised and lowered, to properly position the suction head. Glue rolls 11 are provided in connection with a tiltable glue 80 pot 12, and the pot is tilted so that during advance of carriage 3 (toward the left in Figure 3), the under surfaces of stencil members 5 pass over one of the glue rolls and receive glue to be applied to margins 85 of the blank when the blank comes in contact with the suction head, and in the case of a tight wrapped box, the under surface of the blank carried by the suction head moves over the other glue roll in the retreat 90 of the carriage (toward the right, Figure 3). The cardboard blank is then associated with a cover blank and the blank assembly is 95 folded into box form by mechanism not shown herein.
- As so far described the automatic box machine is substantially in accordance with the disclosure of the above mentioned patent.
- In the box machine, as herein shown, rack 100 bar 7 is driven by a gear 13 mounted on a shaft which also carries a pinion 14, and the pinion is engaged by rack teeth cut on a rack bar 15 which slides in a guide 16 arranged to permit angular movement of the 105 bar and to hold its teeth in contact with the pinion. The forward end of the rack bar is pivotally connected to the upper end of a lever 17, fulcrumed at 18 and provided with a cam roller 19 engaging a cam groove 110 in a cam body 20 secured on the shaft 21, which is one of the main drive shafts of the box machine.
- The framework also supports a table 25 on which shell blanks are positioned by the feed mechanism presently to be described. A representative shell blank B is shown in dotted lines in Figures 1 and 3, positioned on the table by the slide of the feed mechanism. Suction head 4 has been brought over the blank (Fig. 3) by the forward movement of the carriage, and during that movement the surfaces of the stencil strips 5 have been coated with adhesive. Rails 2 are now lowered and the head is brought in adhesive contact with the blank and suction is applied to secure the blank to the head; the rails are raised, lifting the suction head with the blank away from table 25, the carriage retreats toward the right in Figure 3, the 125
- 120
- 125
- 130

under surface of the blank is coated with glue by one of the rolls 11, if a tight wrapped box is being made, or otherwise one of the rolls 11 without glue may be applied to the 5 under surface of the blank to insure the proper coating of its marginal surfaces by the stencils 5; the blank is then associated, at a position not shown here, with a cover blank and is released from the suction head, 10 the carriage returns to the position shown in Figure 3 and the operations are repeated indefinitely and in rapid sequence for the formation of a large number of boxes per minute. It is obviously important in a machine 15 of this type that a shell blank shall be properly presented to the suction head in every cycle of the machine, not only to avoid loss of time and reduction of output due to the failure to feed a blank in each cycle, but 20 also because stencil surfaces of the suction head are glued, and glue is elsewhere present about the machine, and the failure to present and position a blank on the suction head properly results in improper gumming 25 of parts of the mechanism, or the improper application of glue to a cover blank and adhesion of the latter to the suction head, or causes trouble and waste of time to clear away the cover blank for which no shell 30 blank has been presented, and to put the machine in proper condition for further operation.

The card or shell-blank feed mechanism is supported by a framework comprising 35 side uprights 30 and cross members 31 and 32, and a central longitudinal box-like member 33 having spaced vertical side walls 34. This framework may be arranged substantially as a unit and connected as such to the main frame 1, as shown, and table 25 previously mentioned may be supported on the feed frame and specifically on top of side walls 34 of frame member 33.

Bars 35 with smooth flat upper surfaces 45 are secured to the upper edges of member 34 and provide a slideway for the blanks in their movement of table 25, and forward portions of the bars 35 also provide the principal support for the stack S of blanks B. 50 The stack is guided by a vertical back plate 36, located in a channel in the front face of a holder 37 which is secured to a cross bar 38, the ends of which are supported in brackets 39 resting on side frame members 30, and by vertical side plates 40 secured by suitable brackets 41 to cross bar 38. To 55 locate the blank stack longitudinally of the machine and also to allow for different blank dimensions in the longitudinal direction, the entire stack guiding structure may be adjusted by moving brackets 39 longitudinally on the frame members 30. For this purpose the bases of brackets 39 are provided with slots 42 (Figure 1) and cap screws 43 60 passing through the slots secure the guide

structure in the proper adjusted position. To allow for varying blank dimensions in the transverse direction of the machine, the vertical side guides 40 are also adjustable laterally on bar 38 by means of slot and 70 screw arrangements 44, Figure 2.

The lower portion of the vertical back plate 36 is desirably of reduced width, as shown in Figure 2, and the lower end 45 of this plate is located slightly above the level of the tops of bars 35 to provide a gateway for the exit of a blank; and said lower end also acts as a stop to prevent rearward movement of the next superposed blank. To provide for blanks of different 80 thicknesses, plate 36 is arranged adjustably in its channel in the front face of holder 37, and to provide for convenient and accurate adjustment an adjusting screw 46 is provided, passing through lugs 47 and 48 on 85 the plate and holder 37 respectively. The position of the lower end of the plate may be closely and accurately adjusted by turning the screw, and the adjustment fixed by means of a lock nut 49, and the plate may 90 be additionally secured in adjusted position by screw 50 passing through a slot in holder 37.

The forward end of the stack, or especially of the lower portion of the stack, may 95 be additionally guided by short vertical guide rails 51, which are laterally adjustable on rods 52 and these rods are held adjustably in the lateral direction of the machine by thumb nuts 53 on the ends of bars 54, 100 which pass through sleeve sockets 55 on lower portions of guide plates 40 and are secured in said sleeves for adjustment in the longitudinal direction of the machine by set screws 56. In this way an ample range of 105 adjustment of the vertical front rails 51 is obtained for different blank dimensions in the longitudinal direction of the machine and also to bring the vertical edges of the 110 rails in contact with suitable portions of the blank stack, for instance, with edges of certain blank flaps or wings near the ends thereof, as shown in Figure 2. To facilitate placing bunches of blanks on the stack or to guide the lower portion of the stack between 115 guide rails 51 and the back plate 36, the upper inward corners of rails 51 are beveled or rounded as at 57.

A blank feed slide 60 is arranged to reciprocate upon rails 61, in the space between 120 bars 35. One or more blank-engaging or suction gripping devices 62, are secured to the upper surface of the slide. Although different forms of blank grippers may in some cases be used, suction grippers are suitable for the purpose and are employed in the present embodiment of the invention. Each gripper comprises a thin flat top plate 63 provided with a central air opening 64, Figure 1 and a thin rubber cup or washer 65 125

may be provided about the air opening to provide a firm grip on the under surface of the blank when air is exhausted through the opening 64 by means of a flexible air tube 66, secured to a nipple extending downward from the suction fitting. The suction fittings may be secured adjustably on the slide, and for this purpose their nipples are accommodated by a longitudinal slot 67. The upper surfaces of the suction plates 63 are substantially flush with the upper surfaces of bars 35 and the forward one of the plates has a beveled surface 70, the forward end of which is slightly below the level of bars 35, so that the plate will run smoothly under the lower blank of the stack in the forward slide movement; and directly back of the beveled surface 70 is a blank gripping shoulder 71 extending slightly above the level of plates 63 and bars 35, to grip the forward edge of the lowest blank at the beginning of the feed movement. Desirably shoulder 71 is formed on a small plate 72 secured to suction plate 63 by screws 73 to permit the plate to be removed and refinished, or another plate to be substituted, when the shoulder 71 is damaged or worn.

The feed slide may be reciprocated by any suitable mechanism in proper relation to the movement of blank carriage 3. In the present embodiment of the invention, the slide is connected by a bracket 75, Figure 3, to the upper stretch of a chain 76 passing around a drive sprocket 77 on a shaft 78 and a front idler sprocket 79 rotatably mounted in a bracket 80 pivotally secured to frame member 32 at 81, and adjusted by a screw 82 to properly tension the chain. Shaft 78 of sprocket 77 has at one end a gear 85 engaging gear 13 previously mentioned, which drives the carriage rack bar 7. In this way as the carriage moves forward, the upper stretch of chain 76 moves rearward, carrying with it the slide 60 to position a blank carried by the slide upon the table 25 at the moment that suction head 4 is brought over the blank above the table; and when the carriage moves rearward, the slide moves forward to a position under stack S, ready to receive another blank.

To aid materially in separating the lower blank from the one above it, and especially in the case of curved or buckled blanks and those having flaps or wings, for reasons briefly mentioned above and more particularly explained hereafter, additional blank grippers 90 are provided, which desirably, as in the present embodiment of the invention in the form of suction grippers, each include a rubber suction cup 91 mounted on a metal body 92, and each of the bodies 92 is slidably mounted on a rail 93. The rails are of rectangular cross section, so that the suction bodies are supported irrevolubly but are free to slide longitudinally of the ma-

chine. Each of the rails 93 is secured to a lever 95 and the suction bodies are normally held in their forward positions by springs 96 connected to the bodies and to fixed points on the levers.

The upcurved inward ends of levers 95 are pivotally mounted in line with bars 35 at the tops of frame members 33, the bars 35 being interrupted and the frame members 33 also being cut away to permit pivotal movement of the levers. The outer ends of the levers are provided with balls 100 resting in sockets 101 on the ends of levers 102 which are secured to a rock shaft 103 mounted in bearings 104 and provided with an arm 105 carrying a cam roller 106 engaging the periphery of a cam 107 on a shaft 108, which is driven by sprockets and a chain 110 from shaft 21 previously mentioned. The balls 100 and their sockets 101 may be complete socket joints, but open or half-spherical sockets are provided as here shown, and the ball ends of the levers may be held down in the sockets by springs 112.

Air openings are provided at the centers 90 of the suction cups 91, and these openings are connected by suitable pipe fittings 114 and rubber tubes 115 to an air valve body 116; air tubes 66 previously mentioned are also connected to the valve body 116. Since 95 in the present case there are two of the tubes 66 and also two of the tubes 115, each pair of tubes may be connected by a T-fitting 117 to one chamber in the valve body. A valve stem 120 is provided for each valve chamber 100 and the stems are provided with springs 121 and are actuated by bell crank levers 122 and suitable cams 123 adjustably mounted on shaft 108 previously mentioned. A connection 124 leads from the valve body to any 105 suitable exhaust pump or a tank in which low pressure is maintained, and the cams are arranged so that "suction" is applied to the suction cups 91 and also to the suction heads 65 on the feed slide, and the suction 110 is released by re-admitting atmospheric pressure, at the proper time.

A typical cardboard blank B for the feeding of which this mechanism is especially well adapted, is shown in Figure 5. In the production of such blanks from cardboard, whether they are of plain rectangular outline, cornered or provided with wings or flaps as shown in the drawing, and especially when cut from rolled material, the blanks 120 are almost unavoidably warped in one direction, this warpage or curvature occurring in planes perpendicular to the blank surface and parallel to the line 6—6, Figure 5, as more particularly indicated in a slightly exaggerated way in the sectional view, Figure 6, which is in the plane 6—6 of Figure 5. If for any reason the blanks are not appreciably warped, bunches of the blanks may be bent by the attendant before they are 125 130

placed in the stack S. The warpage or curvature of the blanks may consist in some cases simply of the bending of side wings b along creases or fold lines c when the blanks 5 are scored or creased to facilitate subsequent folding.

Cardboard blanks, and especially box blanks, are usually formed with corner cuts, or with end wings d and corner laps e, and 10 the corner laps are frequently bent up at an angle to the side wings b or out of the plane of the end wings d as shown in Figure 5, and such blanks when arranged in a stack frequently have the flaps or corner laps e 15 of one blank more or less interlocked with the end wings d of the next adjacent blank, or the adjacent blanks are more or less interlocked or stuck together in the ways mentioned in the earlier part of this specification. 20 These characteristics of typical blanks have been objectionable in previous feed mechanisms and have interferred with the proper separation and advance of the individual blanks. In automatic box machines 25 of the type here shown, and as disclosed in the prior application above identified, the suction head 4 is brought down upon the upper blank of a stack placed below the suction head in its forward position, corresponding practically to the position of the 30 suction head as shown in Figure 3 herein, and the topmost blank is gripped by suction and by adhesion of glue on the faces of the stencil strips 5, and the blank is then lifted 35 by the upward movement of the suction head; but in many cases the sticking of the blanks due to interlocking of their flaps and other conditions, as sufficiently explained above, caused the next lower blank to adhere 40 to the topmost blank, resulting in the transport of two blanks to the point of assembly with the cover paper or the dropping of one of the blanks somewhere en route, or other difficulties. In other types of feed 45 mechanism the sticking or interlocking of the blanks and the warpage of the blanks has prevented proper feeding. In the present feeding mechanism, however, when the blanks are warped, the warpage is taken advantage of to insure complete separation of the blanks and insure the feed of only one blank at a time from the stack.

In the present invention when the blanks are warped, as above explained, they are arranged with the concave side upward as 55 clearly shown in Figure 3. For warped blanks, also, rear vertical guides substantially in line with the front vertical guides 51 may be provided to space the rear face of the stack slightly away from the gate or center guide plate 36. The arrangement of suitable vertical back guides for curved blanks and the co-operation of the blanks with such guides and with the gate or stop 60 plate 36, are fully explained in connection 65

with the form of the invention shown in Figures 9 to 11. When the blanks are flat their rear edges may rest directly against the vertical plate or stop plate 36.

After a blank is delivered to the suction 70 head 4, slide 60 advances (toward the left in Figure 3), and at any convenient time before the slide runs under the stack levers 95 are raised, bringing suction cups 91 carried by them into contact with the bottom 75 surfaces of end portions of the bottom blank. The suction cups are at this time in their foremost position, that is toward the left in Figure 3, being so held by springs 96. Further upward movement of levers 95 now 80 lifts the stack slightly, sufficient to provide clearance for slide 60 which advances beneath the stack without any frictional contact between the lower blank and the upper 85 surface of the slide, and therefore without any wear on the suction cups 65 carried by the slide, and the slide is then brought to rest with shoulder 71 of suction plate 63 below the forward edge of the lower blank 90 and ready to engage that edge when it is 95 properly depressed. At this time both of the suction devices 61 and 62 are beneath the central portion of the blank and in contact with it. At any suitable time after levers 95 are raised to bring suction cups 91 in contact with the bottom blank, suction 100 may be applied by the suction of the proper air valve to secure the blank portions to the suction devices. After the slide has come to rest just before a feed action, as above explained, cams 123 on shaft 108 operate the appropriate valve stem 120, and suction is applied to the suction devices on the slide. The central portion of the blank is thus 105 tightly held upon the slide 60 and end portions of the blank or portions to each side of the longitudinal center line 6—6, Figure 5, are firmly gripped by suction cups 91. The outer ends of levers 95 are now dropped by the rotation of cam 107 and the bottom 110 blank by the downward movement of suction cups 91 is caused to assume a curvature in vertical planes at right angles to the original curvature, that is, in planes parallel to the section line 7—7, Figure 5. This curving of the bottom blank in the transverse direction of the machine at once eliminates 115 the original curvature without any effect upon the next blank in the stack. The position of the lower part of the stack and the bottom blank at this time is diagrammatically shown in Figure 7, which is a vertical section in the plane 7—7 of Figure 5. Central portions of the blank adjacent to the longitudinal line 6—6, Figure 5, are by this 120 movement straightened out and the rearward edge of the blank, that is, the edge of wing b in the particular blank described, is straightened out and brought below stop-edge 45 of plate 36 and the front edge of the 125 130

blank is also straightened out and brought down into engagement with the feed shoulder 71. The downward bending or curvature of end portions of the blank also, as clearly shown in Figure 7, pulls the end flaps or wings of the bottom blank well down away from corresponding parts of the next upper blank, especially since the corner laps ϵ of that blank remain in an elevated position because that blank retains the original curvature as shown in Figure 6. A very complete and effective blank separation is thus obtained in spite of any original sticking of the blanks or interlocking of their flaps, this result being accomplished by the change in the curvature of the lower sheet while the next upper blank retains its original curvature, and also by the actual vertical removal of end portions of the lower blank from those of the one above it. While suction is maintained in all of the suction devices, slide 60 now commences to move rearward (to the right in Figure 3) while suction head 4 is moving forward. For a small part of this slide movement suction is maintained in the suction devices 91 and they travel along with the blank, sliding on the rails 93 against the pull of springs 96. This condition continues at least until the rear edge of the blank is well away from the forward corner of stop-edge 45. During the sliding movement of the bottom blank away from under the stack, the next upper blank and all those above it are positively prevented from moving rearward by engagement of the rear edges of all of them including the next to the bottom blank with the front face of the vertical guide plate, this engagement of the next to the lower blank being insured by the retention of its original curvature. After the bottom blank has moved a sufficient distance to clear the guide plate 36 the valve controlling suction cups 91 is operated to cut off suction and restore atmospheric pressure and the suction cups are immediately released from the blank and are pulled back by their springs 97 to normal position; and at any suitable time during the remainder of the cycle the cups are again elevated in contact with the stack bottom by upward movement of levers 95. The rearward movement of slide 60 continues, with the blank firmly held on it by the grip of the suction cups 61 and 62 and also by the positive push of shoulder 71 in engagement with the forward blank edge, until the blank is located properly upon table 25 and suction head 4 is brought down upon it, and thereupon suction is cut off from the suction device 62, releasing the blank from the feed slide; the blank is seized by the suction head 4 and raised, slide 60 advances while the suction head is carried rearward by its carriage, and the cycle is repeated indefinitely, a blank being positively separated

and advanced from the stack at each feed movement of the slide with practically no skips or other faulty feed actions.

While the feed mechanism proper as above described is well adapted to and especially valuable in connection with an automatic box machine of the character described, it is evidently capable of use with or adaptable to other machines, or any system of operations wherein it is desired to very positively, accurately and regularly feed individual cardboard blanks from a stack with practically no possibility of skips or other errors.

Figures 9, 10 and 11 show modified feed mechanism also adapted for arrangement as part of another type of blank working or blank handling machine, or for attachment to blank handling or blank working mechanisms in general. The main frame 130 may be a part of a machine for handling or operating upon cardboard blanks, or it may be the frame of the feed mechanism proper and arranged to be applied to or connected as an attachment to a blank handling or blank working machine. Feed rolls 131 and 132 supported by frame uprights 133 may be arranged as a part of the feed mechanism itself, or may be incorporated in the blank handling or blank working machine, as may be convenient or desirable. The feed rolls 131 and 132 may be driven from a suitable part of the feed mechanism proper, or from the machine to which the feed mechanism is attached; and therefore the driving arrangement and other details of the feed rolls are not particularly shown.

The blank stack S is arranged and guided substantially as in the previous example, the rear and side guides being identified by the same numerals as in the previous example. The front guides 135 consist of pairs of vertical rails or strips, each pair being vertically adjustable by slots 136 in the transverse supporting members 137, and screws 138 passing through the slots and engaging the vertical guide rails. The supporting members 137 are secured adjustably to longitudinal bars 54 as in the previous example. The described arrangement is suitable for plain rectangular blanks and the vertical guide rails 135 without lateral adjustment except for the adjustment afforded by the movement of vertical side guide members 40, suffice to properly support and guide blanks of varying width (in the transverse direction of the machine). Other front guide members may be provided for cornered or other peculiarly contoured blanks.

While the blank stack may be partly supported on stationary members, such as bars 35 of the previous described structure, it is sufficient in many cases, as in the present particular embodiment, to support the stack entirely upon a feed slide 140, which is

mounted to reciprocate on a rail 141 secured to transverse frame members 142 by suitable brackets such as 143. The slide supports the stack at all times while it slides under it in its feed and return movements. The slide is provided with a shoulder 145 to engage the front edge of the bottom blank, and desirably this shoulder is formed on a separate block 146 located in a channel 147 on the top of the slide and adjustably secured by means of a screw 148 passing through a slot 149 in the block and engaging one of a series of threaded holes 150 in the slide at the bottom of the channel. By inserting the screw in a selected one of the holes 150 and then by moving the block longitudinally on the slide, a great variety of adjustments may be made, to suit the blank position and also to allow for different blank dimensions longitudinally of the machine.

The slide has depending lugs 155 between which one end of a link 156 is pivotally connected, and the other end of the link is pivotally connected to the upper end of a lever 158 fulcrumed at 159 on a frame bracket, and the lever is operated by a link 160, the rearward end of which is provided with an eccentric strap 161, fitting around an eccentric 162 on an operating shaft 163, which is driven in any suitable way, for example, by a chain or belt 164 connected to a suitable rotating part of the machine in which the feed mechanism is incorporated or to which it is attached, so that the slide is reciprocated by the described linkage in proper unison with the operations of the blank working or blank handling machine.

Pivotally connected to the slide at each side thereof, is a lever 170, the central portion of which is depressed and the outer end of which is provided with a bearing 171 slidably mounted on a longitudinal rod 172. Each of the rods 172 has its ends supported in a forked bracket 173 carried by an upright bar 174, arranged for vertical reciprocation in guides 175. The lower ends of bars 174 are connected by a transverse bar 176; a link 177 is connected to this bar near its center and the upper end of the link is pivotally connected to a lever 178 fulcrumed at 179 and provided with a cam roller 180 engaging a cam track in a cam body 181, fixed on shaft 163. This shaft, as already stated, controls the movements of slide 140 and the cam track is arranged so that the upright bars 174 and the outer ends of levers 170 are elevated at some time before the commencement of a feed movement of the slide, and are depressed just before the feed movement commences, for reasons later explained.

One or more suction cups 184, substantially similar to the suction cups 91 described in connection with the previous example, are carried by each of the levers 170. In

many cases one suction cup on each lever is sufficient and only one is illustrated in the present instance. Desirably, the metal bodies 185 which carry the suction cup are mounted for longitudinal adjustment on bars 186, which are carried by brackets 187 secured to the levers, so that the suction cups may be properly positioned longitudinally under desired portions of the blanks, or in relation to blanks of different lengths in the longitudinal direction of the machine. Each suction cup has a central air passage and the air passages are connected by suitable nipples and flexible tubes 190 to any suitable air exhausting appliance, such as a tank in which low pressure is maintained, or to a suction pump 191, the piston of which is connected by a link 192 to a lever 193, fulcrumed at a convenient point, for instance, on outward end of shaft 179, and the lever is provided with a cam roller 194 engaging a cam track in a cam body 195 on shaft 163 previously mentioned. The cam track is designed so that the pump piston makes a suction stroke commencing just before the advance movement of the blank slide, and suction is maintained during a considerable part or all of the advance movement, this being easily possible because the feed movement of the slide is usually quite short, being only sufficient to carry the rearward edge of a blank from its normal position in the stack to the line of contact of the feed rolls 131 and 132, whereupon the blank is seized by the rolls and further advanced to the machine with which the feed mechanism co-operates. The cam track is further designed so that suction is relieved and atmospheric pressure restored before or substantially at the end of the slide feed stroke.

Suitable valve mechanism, as in the previous example, may, of course, be used instead of the pump, to control the suction.

Flat blanks may be handled by the described mechanism, but the operation will be described in connection with warped or curved blanks.

As previously stated, when the blanks are flat, their rear edges may rest directly against the face of the vertical rear guide plate 36, but as also briefly referred to above, in the case of curved blanks, which straighten out and become longer in the longitudinal direction of the machine when they are flattened out, it is usually preferable to provide vertical rear guide members 190 similar to the front vertical guide members 135. These rear vertical guides are, as clearly shown, located considerably away from the longitudinal center of the blanks and considerably away from the slide and also located in a longitudinal direction of the machine so as to hold the rear blank edges slightly spaced away from stop plate 36 as clearly indicated in dotted lines in Figure 130.

10. In the initial separating action, in which suction cups 184 engage and move downward, end portions of the bottom blank, these end portions are drawn down below the vertical rear guides 190 and as the original curvature is eliminated and the blanks are straightened out in the longitudinal direction of the machine and therefore lengthened somewhat in that direction, there is no resistance to such movement or elongation of the blank by contact with the central vertical guide plate 36. The central portion of the rear edge of the blank is then closely adjacent to the lower end of stop plate 36 but is drawn down below edge 45 and is straightened out in the longitudinal direction of the machine ready to pass through the gateway or space between edge 45, and the slide, this space being usually only sufficient to permit the passage of a single blank. The initial separating action in the case of flat blanks is substantially the same, except there is no original deformation of the blank and it is simply bent in a manner indicated, and this bending causes no elongation of the blank in the longitudinal direction of the machine, and therefore the rear vertical guides 198 may be omitted and the rear blank edges in the stack may rest directly against plate 36.

When the slide is in its foremost position, shoulder 145 engages the front edge of the bottom blank. Just before or as the slide commences to move rearward in the feed direction, levers 170 being at this time elevated and the suction cups 184 in contact with the bottom surface of the lower blanks, suction is applied to the cups causing them to adhere tightly to the blank. The levers are now dropped to the position shown in Figure 9, and end portions of the bottom blank are bent downward, and when the blank is curved or buckled in the manner previously described, the curvature or buckle is eliminated or reversed, and central portions of the blank are flattened out perfectly straight, in the longitudinal direction of the machine, so that the central part of the blank is free under the stop edge 45 and through the gate, while the next superposed blank is stopped by frictional contact with the blank above it, or by positive engagement with the stop plate 36 just above edge 45. During the feed movement of the slide, the blank is firmly held by the suction cups in the described curved position and is positively moved by shoulder 145 in contact with its forward edge, and after a short feed movement the rearward edge of the blank is caught by the feed rolls and then the blank is advanced by the feed rolls to other instrumentalities which act upon it, and just before or as the slide feed movement is completed or about the time the blank is seized by the feed rolls, suction is cut off from the suction

cups 184, releasing the blank. The slide then moves forward (to the left in Figure 11), while suction cups 184 are still in downward position and therefore free from any sliding contact with the bottom blank of the stack during the forward slide movement, and at about the time the slide comes to rest in its forward position levers 170 are again elevated, bringing the suction cups in contact with end portions of the bottom blanks. There is in this case no necessity for further lever movement to lift the stack, the central portion of which may be in sliding engagement with the slide at all times. The suction cups being carried by levers which are pivotally secured to the slide, move with the slide at all times, the outward ends of the levers sliding on the rods 172.

Feed mechanism embodying the invention may be employed merely for feeding the individual blanks from the stack, regardless of the operations which are performed upon the blank; for example, the blanks may simply be fed to an apron which carries them to a point of utilization. In the form of the invention shown in Figures 9 to 11, co-operating rolls 200, 201, carried by frame uprights 202, may perform certain operations, and these parts may be considered as initial members of the blank working machine with which the feed mechanism is in this case associated. A shelf 203 supported on frame uprights 133 and 202 serves in this case to direct the blanks from feed rolls 131 and 132 to the rolls, 200, 201.

The invention, embodied in suitable forms, two of which are here described, works with great accuracy and certainty and many thousands of blanks have been separated and fed in rapid succession without a skip or erroneous feed action, and in fact the mechanism will feed blanks correctly without skipping except where its proper operation is prevented by outside causes, such as an imperfect or torn blank which may not be detected by the operator in placing the blanks in bunches in the stacks. Even in the case of defective blanks, there will be no skip or improper feed action in most cases, unless the defect in the blank is serious and sufficient to render the blank unfit for use for purposes for which it is intended.

The method has been sufficiently explained in detail in the description of the mechanism. Briefly reviewed, the method comprises in its salient features the bending of one blank, or the movement of portions of an end blank of a stack in the general direction of blank thickness to effect an initial separation, and then removing the end blank in a generally edgewise direction away from the stack. Otherwise stated, the method comprises changing the curvature or buckle of the end sheet of a stack of curved blanks to effect initial separation of blank portions

from the stack and to conform or position the blank more favorably for movement from the stack or past a stop or through a gateway; and still otherwise stated, the 5 method comprises bending an originally curved end blank of a stack of such blanks to eliminate the original curvature or to produce a different curvature which may have a convexity opposite to the original 10 convexity, and may also be along a different line or axis from the original axis of curvature, and then moving the blank away from the stack in a generally edgewise direction.

With reference to the blank, words indicating 15 dimensions or directions are usually employed with reference to the location of the blank in the machine. For instance, while the direction or dimension indicated by the line 6—6, Figure 5, represents the shortest or widthwise dimension of the blank, the blank in this case is so placed in the machine that line 6—6 is in the position of the feed slide center line. Sometimes the blank is so placed in the machine that its 20 narrower dimension is transverse the machine and its longer dimension represented by the line 7—7 is in line with the slide. In that case, if the blanks are curved or warped, the warpage would usually be opposite to 25 that shown in Figure 5.

I claim:

1. A method of separating and feeding individual curved sheet blanks having wing formations from a stack of such blanks, 35 comprising bending opposite winged portions of a single blank at the end of the stack away from the next adjacent blank sufficiently to rectify the curvature and to clear the wing formations of the end blank from said next 40 blank while retaining a central portion of said end blank substantially in contact with said next blank, and then moving said end blank away from the stack substantially edgewise while maintaining said winged portions 45 in said bent and separated positions.

2. A method of separating individual curved blanks of flexible sheet material from a stack of such blanks, consisting in bending an end blank of the stack to produce a curvature in another direction from the original curvature sufficient to rectify such original curvature and at the same time to separate end portions of said blank from the next adjacent one, and then moving said end blank by sliding it away from the stack substantially in the direction of one of its curved edges.

3. A method of separating individual curved blanks of flexible sheet material from 60 a stack of such blanks, consisting in bending an end blank of the stack to produce a substantially opposite curvature on an axis transverse to that of the original curvature and at the same time to separate opposite end portions of said blank from the next ad-

jacent one, and then moving said end blank by sliding it edgewise away from the stack substantially in the direction of one of its curved edges.

4. Blank feed mechanism of the class described, comprising a holder for a stack of blanks, feed means for engaging and moving successive end blanks of the stack away from the stack by substantially edgewise movement, grippers adapted to engage portions of said end blanks at opposite sides of said feed means, and means for moving said grippers to engage said end blanks and for then retracting the grippers to bend said blank portions away from the stack to facilitate the stated edgewise feeding operation. 70

5. Blank feed mechanism of the class described, comprising a holder for a stack of blanks, feed means for engaging and moving successive end blanks of the stack away from the stack by substantially edgewise movement, grippers adapted to engage portions of said end blanks at opposite sides of said feed means, and means for moving said grippers to engage said end blanks and for then retracting the grippers to bend said blank portions away from the stack to facilitate the stated edgewise feeding operation, and means supporting said grippers for movement along with said feed means while engaging and holding the blank portions in the stated conditions. 85

6. Blank feed mechanism of the class described, comprising a holder for a stack of blanks, feed means for engaging and moving successive end blanks of the stack away from the stack by substantially edgewise movement, grippers adapted to engage portions of said end blanks at opposite sides of said feed means, and means for moving said grippers to engage said end blanks and for then retracting the grippers to bend said blank portions away from the stack to facilitate the stated edgewise feeding operation, the grippers being arranged and operated 100 so that in their blank-engaging movement they elevate the stack substantially to facilitate movement therebelow of said feed means. 110

7. Feed mechanism of the class described, comprising a stack holder, a feed slide arranged for reciprocation below the holder and provided with blank-advancing means, means for reciprocating the slide, suction grippers arranged at opposite sides of the slide, means supporting said grippers for movement toward and from the stack, and means for operating said supporting means to bring said grippers in contact with a bottom blank and then by retreat to depress end portions of said blank clear of the stack to facilitate 120 edgewise delivery of said blank by the slide.

8. Feed mechanism of the class described, comprising a stack holder, a feed slide arranged for reciprocation below the holder and provided with blank-advancing means, 130

means for reciprocating the slide, suction grippers arranged at opposite sides of the slide, means for supporting said grippers for movement toward and from the stack, 5 means for moving said supporting means to elevate the suction grippers to engage the bottom blank and raise the stack substantially to facilitate movement of the slide beneath the stack, and means for then depressing 10 said supporting means to cause bending of end portions of the bottom blank away from the stack.

9. Feed mechanism of the class described, comprising a stack holder, a feed slide arranged for reciprocation below the holder and provided with blank-advancing means, 15 means for reciprocating the slide, suction grippers arranged at opposite sides of the slide, means supporting said grippers for movement toward and from the stack, and means for operating said supporting means to bring said grippers in contact with a bottom blank and then by retreat to depress 20 end portions of said blank clear of the stack to facilitate edgewise delivery of said blank by the slide, said supporting means also including means admitting of movement of 25 said suction grippers in the direction of slide movement and while in engagement 30 with the blank.

10. Feed mechanism of the class described comprising a blank stack holder, a slide arranged for reciprocation therebelow and having blank engaging means, means for reciprocating the slide, suction gripper supports arranged substantially at opposite sides of the slide, means for raising and lowering the supports, means on the supports for holding suction grippers and admitting movement of said grippers in the direction of slide movement as well as substantially vertical movement with said supports, and means for applying suction to the grippers while elevated to engage end portions of a blank and to maintain the suction while the grippers are depressed and moved with the slide and blank to maintain the blank in stated condition during at least a portion of its movement from the stack.

11. Feed mechanism of the class described comprising a blank stack holder, a slide arranged for reciprocation therebelow and having blank engaging means, means for reciprocating the slide, suction gripper supports arranged substantially at opposite sides of the slide, means for raising and lowering the supports, means on the supports for holding suction grippers and admitting movement of said grippers in the direction of slide movement as well as substantially vertical movement with said supports, means for applying suction to the

grippers while elevated to engage end portions of a blank and to maintain the suction while the grippers are depressed and moved 65 with the slide and blank to maintain the blank in stated condition during at least a portion of its movement from the stack, and means for then breaking the suction to free the grippers from the blank. 70

12. Feed mechanism of the class described, comprising a stack holder, a feed slide arranged for reciprocation below the holder and provided with blank-edge engaging means, suction grippers on the slide, means for reciprocating the slide, other suction grippers arranged at opposite sides of the slide, means supporting said other grippers for movement toward and from the stack and means for operating said supporting 80 means to bring said grippers in contact with a bottom blank and then by retreat to depress end portions of said blank clear of the stack to facilitate edgewise delivery of 85 said blank by the slide.

13. Mechanism for separating and feeding individual blanks from a stack, comprising a stack station, a back stop arranged to permit passage of a single blank and to restrain others of the stack, a slide arranged 90 for to and fro movement below the stack, a shoulder thereon arranged to engage the edge of the bottom blank, suction grippers, one arranged at either side of the slide, means for moving the suction grippers toward and from the stack and for controlling the suction effect to depress end portions of the bottom blank and free them from the next superposed blank, and means by which the suction grippers move along with the 100 slide in its feed movement.

14. Mechanism for separating and feeding individual curved blanks from a stack, comprising a stack station, a back stop arranged to permit passage of a single blank 105 and to restrain others of the stack, a slide arranged for to and fro movement adjacent to an end blank of the stack, a shoulder thereon arranged to engage the edge of an end blank, suction grippers one arranged 110 at either side of the slide, means for moving the suction grippers toward and from the stack and for controlling the suction effect to depress end portions of the end blank of the stack, separate them from the stack and eliminate the original blank curvature and straighten its central longitudinal portion for passage beneath the stop, and means by which the suction grippers move along with the slide in its feed movement. 115

Signed at Brooklyn, in the county of Kings and State of New York this 20th day of July, A. D. 1923.

HARRY BRIDGMAN SMITH.
